UNITED STATES PATENT OFFICE.

JACOB LILL, OF CHICAGO, ILLINOIS.

CORNER-BRACE.

1,392,839.

Specification of Letters Patent.

Patented Oct. 4, 1921.

Application filed March 28, 1921. Serial No. 456,432.

To all whom it may concern:

Be it known that I, JACOB LILL, a citizen of the United States, residing at Chicago, in the county of Cook and State of Illinois, 5 have invented new and useful Improvements in Corner-Braces, of which the following is a specification.

This invention relates to corner braces and an object of the invention is to provide a 10 simple corner brace structure which may be used for bracing corners formed where two members meet, and one which is particularly designed for bracing corners of frames, to greatly increase the strength of the frame 15 and prevent distortion thereof under rough usage or strain applied to the frame transversely of its corners.

Another object of this invention is to provide a corner brace, as specified, which is 20 extremely simple in construction being formed of a single sheet of suitable sheet metal, and one which may be easily and quickly applied by any person, and does not require the services of a skilled mechanic 25 to install it.

A further object of the invention is to provide a corner brace structure as specified which will not detract from the esthetic value of the article upon which it is used 30 thereby particularly adapting it for use in bracing the corners of picture frames or analogous articles.

Other objects of the invention will appear in the following detailed description and in 35 the accompanying drawings wherein:

Figure 1 is a perspective view of a corner showing the improved corner brace applied.

Fig. 2 is a section through the corner brace taken on the line 2—2 of Fig. 1.

40 Fig. 3 is a cross section taken on the line 3—3 of Fig. 2.

Fig. 4 is a plan view of a blank from which the corner brace is formed.

Fig. 5 is a perspective view of the corner 45 brace before being applied showing different positions of parts thereof in dotted lines.

Fig. 6 is a section through a modified form of the corner brace.

Fig. 7 is a transverse section through the 50 modified form of corner brace taken on the line 7—7 of Fig. 6.

Fig. 8 is a detailed perspective view of a channel member adapted to be used in connection with a braced frame when the latter 55 is slidably supported.

Referring more particularly to the drawing, the improved corner brace structure 1 is formed of a sheet of metal, preferably rectangular in shape, however, the shape of the blank of sheet metal depends upon the 60 number of angles to the corner or corners to be braced, for instance, when bracing right angle corners the blank would be rectangular in shape, preferably square, while in bracing corners of either greater or less 65 angles than a right angle the metal blank would be shaped accordingly. In forming the corner brace the blank 2 of sheet metal has its corners cut away as shown at 3 providing substantially rectangular portions 4 70 at each side of the blank, and the blank is bent upon itself diagonally, or from the corner of one of the cutout portions 3 to the corner of the cutout portion 3 directly opposite therefrom as shown in Fig. 5 of the 75 drawing, after which the sections 4 are bent at right angles to the flat engaging or abutting portions of the blank, as shown in dotted lines in Fig. 5 of the drawing, providing portions for abutting engagement with the 80 outer surfaces or edges of the articles or members which form the corner to be braced. In applying the corner brace; the members, such as A and B which are placed in engagement to form the corner to be braced 85 are split as at 6 across the corner between their sides, as clearly shown in Fig. 1 of the drawing and the folded corner brace structure 1 has the abutting portions 7 and 8 placed in the slot 6 while the angled clamping portions 4 engage the outer edges of the members A and B upon opposite sides of the slot 6. The edge portions 9 of the angled clamping portions 4 are bent over against the outer surfaces of the members A and B 90 and in abutting engagement therewith. Suitable nails, rivets, or the like 10, are then driven through the angle portions 9, members A and B and the abutting portions 7 and 8 as shown in Fig. 3 of the drawing, 100 thus securely locking the corner brace structure 1 in position and reinforcing the corner to the tensile strength of the metal of which the corner brace structure is formed to make it practically impossible to distort the frame 105 or article formed by the members A and B at the corners.

In Figs. 6 and 7 of the drawing a slight modification of the corner brace structure is shown, the said modified form being de- 110

signed for bracing a corner from the internal angle thereof in lieu of the external corner as illustrated in Figs. 1 to 5 inclusive. The modified form of angle brace 5 structure 20 is constructed of a sheet of suitable sheet metal and is doubled upon itself to provide abutting portions 21 which engage in the slot 22 in the members D and E and is also bent to provide transversely extending clamping portions 23 which engage 10 the inner edges of the members D and E upon opposite sides of the slot 22 as clearly shown in Fig. 7 of the drawing. The edge portions 24 of the side clamping portions 23 are bent to engage the outer surfaces of the members D and E and nails or rivets 25 may be inserted there through as indicated 15 in dotted lines in Fig. 7 to securely anchor the corner brace 20 in place.

20 While the corner braces, shown in the drawing are designed for use in bracing right angled corners of a frame, however, it is to be understood that the corner braces may be made to brace corners of greater or 25 less angles than a right angle without departing from the spirit of this invention and that they may be used for bracing corners of boxes, picture frames, window screens or any 30 analogous structure where it is desired to provide rigid construction.

In window screen construction, a channel structure 30 as shown in Fig. 8 of the drawing may be provided, it being nailed or suitably attached to a window frame to slidably 35 receive the frame formed of the brace members and in such a construction flat springs 31, as indicated by dot and dash lines in Fig. 2 of the drawings, may be attached to the edges of the sides of the frame for frictionally 40 engaging in the channels 30 to hold the screen structure in adjusted position.

It is, of course, to be understood that the invention may be constructed in various other manners and the parts associated in 45 different relations and, therefore, I do not desire to be limited in any manner except as set forth in the claims hereunto appended.

Having thus described my invention what I claim is:

50 1. As a new article of manufacture, a corner brace formed of a rectangular sheet of metal bent diagonally to provide abutting

portions, the edge portions of said sheet bent transversely to the abutting portions to form clamping portions. 55

2. As a new article of manufacture, a corner brace formed of a rectangular sheet of metal having its corners cut away and being bent diagonally to provide abutting portions, the edge portions of said sheet bent 60 transversely to the abutting portions to form clamping portions.

3. As a new article of manufacture a corner brace formed of a rectangular sheet of metal having its corners cut away to provide 65 right angularly sided recesses at the corners of the sheet, said sheet being bent diagonally to provide substantially parallel abutting portions, the edge portions of said sheet of metal formed by the cutting out of said corners adapted to be bent transversely to the abutting portions and about the article to be braced. 70

4. The combination with a pair of meeting members forming a corner, said members slotted at the corner, of a corner brace comprising a sheet of material inserted in said slot and having certain of its edge portions extending out of the slot and bent to engage the outer surface of the meeting members. 75 80

5. The combination with a pair of meeting members forming a corner, said members slotted at the corner, of a corner brace formed of sheet material bent to provide substantially parallel abutting portions, said abutting portions inserted in said slot and having their edge portions extending out of the slot, said edge portions bent to engage the outer surfaces of the meeting members. 85 90

6. The combination with a pair of meeting members forming a corner, said members slotted at the corner, of a corner brace formed of sheet material bent to provide substantially parallel abutting portions, said abutting portions inserted in said slot and having their edge portions extending out of the slot, said edge portions bent to engage the outer surfaces of the meeting members, and anchoring means inserted through 100 said edge portions, abutting portions, and meeting members. 95

In testimony whereof I affix my signature.
JACOB LILL.
